APPARATUS FOR CUTTING A CONTINUOUS LENGTH OF MATERIAL AT INTERVALS

Norman Walter Jackson, Deptford, London, England, assignor to Molins Machine Company Limited, London, England, a British company

Application November 23, 1954, Serial No. 470,738

Claims priority, application Great Britain November 26, 1953

3 Claims. (Cl. 146—95)

This invention concerns improvements in or relating to apparatus in which a continuous length (e. g. stream) of material is cut into separate lengths while being fed lengthwise. One example of such apparatus is a continuous rod cigarette-making machine for making mouthpiece cigarettes, in which a continuous stream of unwrapped tobacco is fed lengthwise and is cut at intervals to produce separate lengths of tobacco which can be spaced apart endwise to enable mouthpiece portions to be inserted between them, and a continuous tobacco filler, consisting of tobacco lengths and mouthpiece portions in alternation, can thus be formed.

In those constructions a stream of unwrapped tobacco is severed at intervals by a narrow knife blade which cuts across the tobacco stream. The knife blade is mounted on a rotating knife holder and cuts the stream once during each revolution of the knife-holder. Thus, if the knife is arranged with its cutting part at a conveniently short distance from its axis of rotation, its speed in passing through the stream may be less rapid than is desirable in order to make a clean, square cut and to avoid holding up the moving stream, or of the length cut from it, by the blade passing through the tobacco.

According to the present invention there is provided apparatus in which a continuous length of material is cut into separate lengths while being fed lengthwise (e. g. apparatus for making mouthpiece cigarettes, in which a stream of unwrapped tobacco is cut into lengths) comprising cutting means to cut the continuous length of material at desired intervals, the said means comprising a rotatable cutter arranged to be moved (e. g. swung) bodily to and from a cutting position at which it can cut the said continuous length, and arranged to rotate through more than one complete revolution during each bodily movement to and from said cutting position.

The expression "continuous length of material" as used herein is to be understood as including any continuous length of material adapted to be cut into separate lengths while moving lengthwise. One example of such a continuous length is a continuous stream of unwrapped tobacco as referred to above. A further example is a continuous cigarette rod formed on a cigarette-making machine, while a still further example is a composite rod consisting of lengths of tobacco and mouthpiece material in alternation.

Preferably the said rotatable cutter comprises a narrow knife blade mounted on a rotating knife-holder.

The apparatus may comprise a rotatable driving member and a driving connection between said driving member and said cutter whereby the latter is rotated at a greater angular speed than that of the driving member, the said cutter being arranged for bodily swinging movement to and from said cutting position, and connected to said driving member so as to be swung in timed relationship with the rotation of said driving member.

The said driving connection for the cutting means may comprise a driven member rotatable with said cutter and a further rotatable member arranged to drive said driven

2

member and about whose axis the said cutter and driven member are arranged to swing, the said further rotatable member being arranged to be rotated by said rotatable driving member.

- 5 The cutter may be connected to said rotatable driving member by linkage connecting the latter to a swingable part in which the cutter is mounted for rotation. The said linkage may comprise a crank on said driving member and a link connecting said crank to said swingable part whereby the latter is caused to swing through a complete cycle during each revolution of said driving member.

Further according to the invention there is provided cutting mechanism comprising a rotatable cutter, a rotatable driving member, gearing connecting said driving

- 15 member to said cutter to cause the latter to rotate at a greater angular speed than that of the said driving member, said gearing including a driven gear rotatable with said cutter and a further gear in driving engagement with said driven gear and about whose axis of rotation the said 20 driven gear and said cutter are arranged for bodily swinging movement so as to cause the cutter to swing to and away from a cutting position, and linkage connecting said driving member to said cutter and driven gear so as to cause the cutter and driven gear to be swung about said 25 axis in timed relationship with the rotation of said driving member.

The said linkage may comprise a crank on said driving member and a link connecting said driving member to a swinging part in which said cutter and driven gear are 30 rotatably mounted.

- As the cutter and the driven gear which rotates therewith are bodily swingable about the axis of rotation of a further gear which drives the driven gear, the speed of rotation of the cutter will vary since the driven gear will 35 roll on the said further gear first in one direction and then in the other as it swings to and fro. For this reason the angular speed of the cutter is not in a fixed ratio to that of the rotatable driving member, but is nevertheless at all times determined by the angular speed of the driving 40 member. As it is desired to cause the cutter to rotate at a relatively high speed, the mechanism is preferably arranged so that the cutting occurs at a time when the driven gear is being swung in opposition to the direction of rotation of the said further gear which drives it, so that the cutter is at the moment of cutting rotating at its maximum speed.

Apparatus according to the invention will now be described by way of example with reference to the accompanying drawings in which:

- 50 Figure 1 is a side elevation of apparatus for making mouthpiece cigarettes, in which a continuous stream of tobacco is cut at intervals and stubs are inserted between cut lengths of tobacco;

55 Figure 2 is a sectional side view of cutting apparatus; Figure 3 is a view taken on the line III—III in Figure 2; and

Figure 4 is a side elevation of some of the apparatus shown in Figure 2.

- 60 Referring first to Figure 1, the apparatus illustrated comprises a tobacco tape 1 arranged to be moved beneath a hopper (not shown) through a trough 1a at varying speeds. A guide tube 2 and a further guide tube 3 are provided to receive a tobacco stream from the tape 1 and guide it on to a paper web 4 carried by a tape 5. Cutting mechanism, which will shortly be described, is provided in order to cut the stream at intervals between the tubes 2 and 3.

65 The variation of the speed of the tape 1 is effected in any convenient way. The speed variation is such that the speed of the tape is greatly reduced immediately after each cutting operation so as to allow a space to develop between the cut length, which is fed forwardly by the

paper web, and the leading end of the uncut stream. Thereafter the speed of the tape 1 is increased to a speed such as to enable it to deliver the uncut filler on to the paper web at substantially the speed of the web 4, and the uncut filler is thus fed on to the paper web at that speed until the next cutting operation.

The cutting mechanism, illustrated in outline in dotted lines in Figure 1, is best shown in Figures 2, 3 and 4. It comprises a rotatable knife carrier 6 in which is clamped a thin, narrow knife blade 7 adapted to pass through the space between the tubes 2 and 3 on each revolution of the knife carrier 6. The carrier 6 is fixed at one end of a shaft 8 which is rotatable in bearings 9 mounted in a swingable bracket 10. At the other end of the shaft 8 is fixed a gear 11 having 22 teeth, which gear meshes with, and is arranged to be driven by, a further gear 12 which has 60 teeth.

The gear 12 is formed on a sleeve 13 on which is also formed a gear 14 which has 30 teeth. The gear 14 meshes with, and is driven by, a main driving gear 15 fixed on the end of a driving shaft 16. The gear 15 has 55 teeth.

Thus the angular speed of the gear 15 relatively to the gear 11, and to the knife carrier 6, is 1 to 5.

The swingable bracket 10 which carries the shaft 8 is arranged to swing about a fixed shaft 17. The sleeve 13 with gears 12 and 14 is also freely rotatable in bearings 18 about the shaft 17. Thus the knife carrier 6 is bodily swingable, with the bracket 10, about the axis of rotation of the gear 12 which drives the gear 11 to rotate the knife carrier.

The main driving gear 15 has fixed to it a crank disc 19 which has formed on it an eccentric boss 20 on which is pivoted a link 21. The bracket 10 has an extension 22, whose shape can best be seen from Figures 3 and 4, and the link 21 is pivoted to this extension so as to provide a linkage connecting the driving gear 15 to the knife carrier 6 and driven gear 11. In Figure 3 is shown, in the dot and dash line marked P, the circular path of the eccentric boss 20 on rotation of the gear 15. As will be seen, this arrangement causes the bracket 10 to swing to and fro about the shaft 17 once during each revolution of the gear 15, during which period of course the driven gear 11 and knife carrier 6 turn through five revolutions.

The throw of the crank 20 and the linkage between it and the bracket 10 is such that the knife 7 is caused to pass between the guide tubes 2 and 3 only once during each revolution of the gear 15, although during this period the knife carrier rotates through five revolutions.

For convenience of illustration the angular position of the knife 7 as shown in Figure 3 is 90° different from that in which the knife is shown in Figure 2, while in Figure 1 in order to show the knife in full lines it has been illustrated in a still different position.

The purpose of the arrangement just described is to cause the knife 7 to rotate at a high speed so as to pass rapidly through the stream of tobacco moving through the guide tubes 2 and 3. As the knife is brought into a cutting position only once during each revolution of the gear 15 and driving shaft 16, the interval between successive cuts is determined by the speed of rotation of the shaft 16.

The swinging of the bracket 10 about the shaft 17 causes gear 11 to roll on gear 12. Accordingly the speed of rotation of the gear 11 and the knife carrier 6 varies according to the direction in which they are swinging with the bracket 10. As the purpose of this apparatus is to increase the cutting speed of the knife, the mechanism is accordingly so arranged and timed that the knife 7 passes between the tubes 2 and 3, to cut the tobacco stream, at an instant just after the bracket 10 has completed its swing in a direction towards the guide tubes (i. e. towards the right in Figure 3) and has started to swing in the reverse direction. In this reverse direction (i. e. towards the left in Figure 3) the rolling of the gear

11 over the gear 12 is opposed to the direction of rotation of the gear 12, and thus the gear 11 is rotated at a faster speed than would be the case if the bracket 10 were stationary. Thus in the arrangement described and shown, at the moment when the knife cuts the stream, the gear 11 and knife carrier 6 are rotating at a speed in the region of six times the speed of rotation of the gear 15 and main driving shaft 16.

It will be appreciated that in a case where a knife is arranged to cut the tobacco stream once during each revolution of its carrier, in order to enable the knife to move, during cutting, at anything approaching the speed of the knife 7 in the arrangement just described, it would be necessary to mount it at an inconveniently great distance from its axis of rotation.

As both the rotation and the swinging of the knife carrier 6 are controlled by the driving shaft 16, the timing of the cutter for different lengths which it may be desired to cut from the stream is easily adjusted by varying the speed of rotation of the shaft 16.

The remaining parts of the apparatus shown in Figure 1 will be briefly described, since they concern the insertion of stubs into spaces between cut lengths of tobacco and as such form no part of the present invention.

This mechanism comprises a stub-wheel 23 mounted for rotation, in the direction shown by the arrow, on a shaft 24 (see also Figure 2). The stub-wheel 23 is formed as a disc having a concave rim as indicated at 25, and provided with three projecting pusher-pins 26. Above the wheel 23 is a stub-feeding device (not shown) comprising a fluted drum by which double-length stubs are intermittently fed down in succession to a position to be engaged by each of the pins 26 in turn. An arcuate guide 27 is provided to guide stubs and prevent them from falling away from the rim of the wheel 23 until they reach a position at which they are to be deposited on the paper web 4.

The wheel 23 is driven by a chain 28 passing over a sprocket 29 fixed to the wheel. The chain 28 is driven by a sprocket 30, which has fixed to it a gear wheel 31 which meshes with a driving gear 32 fixed on a driving shaft 33 which rotates in the direction indicated by the arrow. The sprocket 30 and gear 31 are mounted in a bracket 34 which is freely pivoted about the shaft 33. Also mounted on the bracket 34 is a cam-following roller 35, which is capable of engaging a cam consisting of a rotatable eccentric disc 36. A spring 37 fixed on the bracket 34 urges the bracket about its pivot so as to press the cam-follower 35 against the rim of the eccentric disc 36. It should be noted here that the eccentricity of the disc 36 is very small and cannot easily be perceived in the drawing.

The chain 28 also passes over a guide sprocket 38 mounted on a pivoted arm 39 which is urged about its pivot in a clockwise direction by a spring 40, so as to cause the chain to be kept tight.

The cam disc 36 is arranged to cause the bracket 34 to swing slightly to and fro about the shaft 33 three times during each revolution of the wheel 23. When the bracket 34 swings clockwise, as viewed in Figure 1, the sprocket 30, being carried towards the left in the figure, imparts a small increment to the speed of the chain 28 in excess of that given to the chain by rotation of the sprocket 30. On the return swing the speed of the chain 28 is correspondingly slightly reduced. These swinging movements are so timed as to cause the wheel 23 to move at the faster speed as a pin 26 is approaching the paper web 4 and pushing a stub into a space between a cut tobacco length and the uncut tobacco stream. Immediately thereafter the return swing of the bracket 34 causes the wheel 23 to slow down so that the pin 26 moves with a forward speed approximately that of the paper web.

The driven gear 31 rotates at two-thirds the angular speed of the driving gear 32, and at twice the angular

speed of the sprocket 29 and wheel 23. Thus the wheel 23 makes one revolution during every three revolutions of the driving shaft 33.

A tobacco-engaging element 140 with a serrated end 41 is pivoted at 42 on an arm 43 and is also pivoted at 44 on a crank disc 45, by which its serrated end is caused to move into and out of the path of tobacco lengths and stubs on the paper web, following the path indicated in dot-and-dash lines, and traveling towards the left, in Figure 1, when moving in its lower path. The element 140 performs this movement three times during each revolution of the stub-wheel 23, and is timed and arranged to engage tobacco immediately behind each stub inserted by the stub-wheel, and to move at approximately the speed of the paper web 4 while so engaging tobacco. To engage the tobacco it passes through a slot 46 in a tongue 47.

The apparatus as a whole operates as follows. The tape 1 carries a continuous stream of tobacco and delivers it through the guide tubes 2 and 3 on to the paper web 4. Periodically the speed of the tape 1 is temporarily greatly reduced and just before each such speed reduction the knife 7 is caused to pass between the two guide tubes so as to cut the stream. The cut length continues to move with the paper web, while the uncut stream lags behind until the speed of the tape 1 is again increased. By that time a space has been developed between the cut length and the leading end of the uncut stream. A double-length stub is inserted into this space by a pusher pin 26 on the stub-wheel 23, which moves at varying speeds so that the stub is pushed into the space with a faster forward speed than that of the paper web and the tobacco carried thereby, and immediately thereafter the wheel slows down slightly so that the pusher pin moves with a forward speed approximately the same as the paper speed. As the tobacco and stubs pass beneath the tongue 47 the element 140 engages the tobacco immediately behind the stub and moves forwardly with it at approximately the speed of the paper web, thus controlling the tobacco speed and preventing it from lagging behind the stub.

Subsequently the paper web 4 is wrapped and secured about the tobacco and stubs to form a continuous composite rod, which is cut at appropriate intervals to produce mouthpiece cigarettes.

The lengths of tobacco cut from the tobacco stream are each double the length required in the tobacco portion of a mouthpiece cigarette, and thus the composite rod is cut midway through each tobacco portion and through each double-length stub.

The timing of the cutting mechanism and the timing of the means to vary the speed of the tape 1 are of course correlated according to the intervals at which it is desired to cut the stream, which depends upon the size of cigarette to be made. It will be seen, also, that the speed of rotation of the stub-wheel 23, and the timing of the element 140, must also be correlated with the

operation of the cutting mechanism. Accordingly the cutting mechanism, the stub wheel, and the element 140, as well as the means for varying the speed of the tape 1, can all be driven from a common source through suitable gearing.

What I claim as my invention and desire to secure by Letters Patent is:

1. In apparatus for cutting a continuous length of material at intervals, cutting means comprising a swingable knife support member, a rotatable fly knife carried by said support member, a driven gear carried by said support member and rotatable with said knife to rotate the latter, a driving gear in driving engagement with said driven gear, said knife support member being mounted for oscillatory swinging movement about the axis of said driving gear, means to rotate said driving gear, and means to oscillate said knife support member in timed relationship with the rotation of said driving gear so as to move the rotating knife bodily back and forth toward and away from a position at which it can cut the said continuous length of material.

2. Apparatus as claimed in claim 1, wherein the means to rotate said driving gear comprises a further gear wheel, and the means to oscillate the knife support member comprises a crank on said said further gear wheel, and a link connecting said crank to said knife support member whereby the latter is oscillated through a complete cycle during each revolution of said further gear.

3. A cutting device for cutting a continuous length of material at intervals, comprising a driving shaft, a first driving gear mounted on said shaft, a further shaft parallel with said driving shaft, a first driven gear rotatable on said further shaft and meshing with said first driving gear, a second driving gear rotatable with said first driven gear on said further shaft, a knife support member swingably mounted on said further shaft for oscillation about the axis of the latter, a second driven gear rotatably mounted on said knife support member and meshing with said second driving gear, a fly knife carried by said knife support member and rotatable by said second driven gear, a crank on said first driving gear, and linkage connecting said crank to said knife support member so as to oscillate the latter through a complete cycle during each revolution of said first driving gear, whereby the said knife is moved bodily by said knife support member toward and away from a cutting position, the ratios of said driving and driven gears being such that the knife rotates through a plurality of revolutions for each revolution of said first driving gear.
